Fig. 2.

<img alt="A detailed technical illustration of a bridge structure, labeled Fig. 3. The bridge features a central support with a central pier (14) and a central roadway (15). The bridge deck (16) is supported by piers (3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 259, 260, 261, 262, 263, 264, 265, 266, 267, 268, 269, 270, 271, 272, 273, 274, 275, 276, 277, 278, 279, 279, 280, 281, 282, 283, 284, 285, 286, 287, 288, 289, 289, 290, 291, 292, 293, 294, 295, 296, 297, 298, 299, 299, 300, 301, 302, 303, 304, 305, 306, 307, 308, 309, 309, 310, 311, 312, 313, 314, 315, 316, 317, 318, 319, 319, 320, 321, 322, 323, 324, 325, 326, 327, 328, 329, 329, 330, 331, 332, 333, 334, 335, 336, 337, 338, 339, 339, 340, 341, 342, 343, 344, 345, 346, 347, 348, 349, 349, 350, 351, 352, 353, 354, 355, 356, 357, 358, 359, 359, 360, 361, 362, 363, 364, 365, 366, 367, 368, 369, 369, 370, 371, 372, 373, 374, 375, 376, 377, 378, 379, 379, 380, 381, 382, 383, 384, 385, 386, 387, 388, 389, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, 2061, 2062, 2063, 2064, 2065, 2066, 2067, 2068, 2069

Attorney

UNITED STATES PATENT OFFICE.

HAROLD SHEMVELL, OF BIRMINGHAM, ALABAMA, ASSIGNOR, BY MESNE ASSIGNMENTS, TO BIRMINGHAM DISC HARROW COMPANY, OF BIRMINGHAM, ALABAMA.

FLEXIBLE DISK HARROW.

1,241,774.

Specification of Letters Patent.

Patented Oct. 2, 1917.

Application filed March 6, 1912, Serial No. 681,928. Renewed March 15, 1917. Serial No. 155,089.

To all whom it may concern:

Be it known that I, HAROLD SHEMVELL, a citizen of the United States of America, residing at Birmingham, in the county of Jefferson and State of Alabama, have invented 5 certain new and useful Improvements in Flexible Disk Harrows, of which the following is a specification.

My invention relates to certain novel and 10 important improvements in flexible harrows which comprise a series of flexibly connected shafts or disk bearings upon which are mounted, for free rotation, series of sharpened disks adapted to have closely 15 associated lines of travel so that they thoroughly pulverize the ground as the harrow is drawn along, each disk having a separate path, and acting to cut the clods to pieces and open up the soil.

20 The objects of my present invention are:

1st: To couple the shafts or disk bearings in such manner that without interfering with their free vertical play which permits them to follow the irregularities of the 25 surface of the ground, the flexible frame as a whole is held against lateral or sidewise play which would permit the disks to track. This I accomplish by increasing the width of the bearings at the ends of the connecting 30 rods and so distributing the rods over the frame that they constitute connections which hold the frame with substantial rigidity against angular play in horizontal plane and yet leave the shafts free to rise and fall in 35 vertical planes.

2nd: To further improve the manner of coupling the disk bearing shafts by the use of arched connecting rods and by connecting said rods to the shafts so that they are preferably equi-distantly spaced from the two 40 disks that are adjacent to each of their ends. This arching of the connecting rods has the advantage of raising the body portions clear of the ground to avoid increasing the 45 draft strain when the harrow is cutting deep and the shape and position of the rods, relatively to the disks, gives them the novel function of tending to force the clods toward the cutting disks so they will not 50 tend to roll through the harrow and escape being cut to pieces.

3rd: To improve both the action of the 55 disks and their construction by forming them of sheet steel and riveting the steel disks between flanged hubs which serve to

space them from each other and from the connecting rods. The thin sharpened edges of the disks will cut the clods to pieces and enter deeply into the subsoil to open it up, while the flaring hubs turn and pulverize 60 the surface soil.

4th: To provide novel means for weighting the harrow and furnishing a seat for the driver. The seat and weighting means should be adapted to distribute their weight 65 substantially uniformly over the several disk shafts and to this end I provide loosely connected supports for the seat or the weight platform, or for a combined seat and weight platform, which supports are 70 adapted to be mounted in such manner as to bear on each shaft and yet not to interfere with the flexibility of the harrow which is essential to its successful operation.

5th: To improve the harrow by providing a means to minimize the tendency of the draft strain to raise the front row of disks from the ground thereby lessening their cutting action.

My invention further comprises the details of construction and arrangement of parts which in their preferred embodiment only are hereinafter more particularly described by reference to the accompanying 85 drawings, in which:—

Figure 1 represents a side elevation of my improved harrow cultivator.

Fig. 2 is a plan view of same partially broken away.

Fig. 3 is a vertical sectional view taken along the line $\alpha-\alpha$ of Fig. 2, and showing part of the harrow in front elevation.

Similar reference numerals refer to similar parts throughout the drawings.

According to the drawings I provide a series of five shafts 1, which are of equal length and arranged in echelon or stepped relation. These shafts or rods are connected by links 2 which are arched in side elevation and have perforated ends in which the shafts are adapted to turn freely. At the outer ends of each shaft I provide cotter keys 3 or like detachable retaining means and between such means and each adjacent link 2 I interpose a ground cutting disk which is preferably formed by an annulus 4 of flat sheet steel with its outer peripheral edge sharpened. The inner peripheral edge of the annulus is fastened by countersunk 105 110

bolts or rivets 5 between the flanges 6 of two hub sections 7 and 8, which flanges taper in cross section on a gradual concave curve from their sharpened peripheral edges, which lie against the opposite sides of the annulus until they merge into the cylindrical body portions of the hubs. These hubs therefore are hollow and provided with annular chambers which are packed with grease when the hubs are mounted on the shafts. The hub sections 7 of the end disks are made shorter than the standard sections 8 to reduce the shaft length and the cylindrical body portions of the hub sections are hollowed out so as to provide relatively narrow bearing surfaces 9^a at each end which supports the disks for rotation on the shafts 1 with a minimum friction. The inner hub section 8 of each end disk abut against an end 9 of the adjacent connecting rod 2. The hub sections of the intermediate disks on the three intermediate shafts will be equal in length and similar to the standard section 8 and the disks will be spaced by the ends 9 of two reversely disposed links 2. The disks on the front and rear shafts are not spaced by two link ends 9 as in the case of the disks on the other or intermediate shafts. To maintain the proper spacing of their front and rear disks, one hub portion 10 of each disk is made longer to compensate for the missing end 9 of a link. In the case of the disks between which the link ends 11 are interposed, it will be noted such ends 11 are made twice the width of ends 9 and hence I use standard hub portions 8 on such disks.

The echelon arrangement of shafts, the construction of the disks and the manner of spacing them by the connecting rods, produces a harrow wherein the several disks stand in diagonal rows extending from front to rear of the harrow, each disk having a separate and distinct line of travel, which several lines of travel are preferably closely associated and equi-distantly spaced, for it will be noted that the front disk of the outer row will have its line of travel equi-distantly spaced from the lines of travel of the second disk in the outside diagonal row and the last disk in the diagonal row next to the outside row (see Fig. 3). To most effectively work the surface of the ground, I make the transverse thickness of the disks at the ground level (Fig. 3) substantially equal to the spacing between the lines of travel of the disks. This causes the front disk of a diagonal row to spread the dirt over into the path of the next succeeding disk which throws the dirt back into the furrow of the front disk.

The links 2 are preferably arranged in diagonal rows interposed midway between the diagonal rows of disks on the shafts. Since the shafts 1 are loosely pivoted in the ends

of the links the harrow as a whole possesses great flexibility, permitting each transverse row of disks to independently rise and fall and have angular play in a vertical plane in following its work without disturbing the work of the adjacent connected rows of disks. The links however have sufficient bearings at their ends to hold the shafts against angular play in a horizontal plane and, by preventing any tendency of the disks to track or follow each other to maintain the line of travel of each disk properly spaced from the lines of travel of the other disks. 70

I provide the two end links and the intermediate link in line with the middle disk on the middle shafts with special ends 11 which have double width bearings to better stand the turning strains, and extensions 12 which extend upwardly above and beyond the peripheries of the front disks and are perforated to provide alining openings which receive a rod 13. Cotter pins 14 hold the rod in position and sections of pipe 15 which are slipped over the rod brace the extensions 12 together to better withstand the lateral thrust when the team is turning the harrow. I provide eyes 16 in the ends of extensions 12 and connect each by a chain 17 to the draft rigging 18 by which the harrow is pulled and which stands opposite the intermediate end 11 and in line with the center of the harrow as a whole. The draft strain coming through the raised extensions 12 tends to force the front disks downwardly 95 instead of lifting them from the ground. 95

For certain classes of work it is desirable to weight the harrow and to provide it with a seat for the driver without interfering with its flexibility or unevenly distributing the work on its several disks. To this end I provide a weight receiving and seat supporting frame formed by transverse bars 19 and 20 connected at each end to an arch bar 21. These latter bars have bifurcated ends 23 oppositely offset to slip over the tops of links 2, the ends of the bars astride the links extending to the front and rear shaft, being pivoted thereto by pivot pins 22. The inner end of each arch bar rests slidably on 110 and free of fixed connection with the adjacent link in its respective diagonal series of links. Cross bars 24 are riveted or bolted to bar 19 and slide in blocks 25 bolted to bar 20. The bars 19, 20 and 24 thus form a raised skeleton platform to receive logs or other weights and to support the seat 26 which is mounted on bars 27 bolted to the bars 24. The weight of the driver and such additional weight as may be on the platform 120 is distributed uniformly on links 2, in the ends of which the several shafts 1 are journaled. As the harrow works over uneven ground the inner ends of the arch bars 21 125 will slide on the intermediate links 2 and 130

the bars 24 will slide in the clips 25 so that no positive or rigid connections are provided to interfere with the flexibility of the harrow. The arrangement of five shafts is preferred as it permits the weight and seat platform to distribute its pressure uniformly on all the disks, otherwise the number of shafts may be varied.

To hold the inner sliding ends of the arch bars 21 against becoming disengaged from their respective supporting links 2, I make the legs of each such end long enough to extend below the link 2 that they straddle and pass a bolt or pin 28 through them (see Fig. 1) disposing it so that it will not interfere with the free movements desired between the arch bars or links.

The extended cylindrical body portions of the hubs serve as roller surfaces which surround the shafts and reduce the friction. They also serve as a spacing means in conjunction with the links, thereby avoiding the use of any extra spacing parts and leaving the disks free on the shaft for independent rotation.

The harrow may be readily turned or if desired may be reversed by transferring the draft connections and bracing means to the extensions 12 on the rear shaft.

Having thus described my invention, what I claim as new and desire to secure by Letters Patent, is:—

1. A flexible disk harrow, comprising disk bearings, straight cutting disks rotatably mounted on the bearings, and means to loosely connect the bearings to form a flexible frame work in which the bearings are adapted to rise and fall freely to follow the irregularities of the ground, said disks being distributed in stepped series over said frame work to have different but closely associated lines of travel, and said means which connect said bearings having sufficient bearing engagement axially of said disk bearings to hold the bearings against relative lateral displacement which will substantially disarrange the predetermined spacing between the lines of travel of the disks.

2. In a flexible harrowing and cultivating implement, a flexible frame work comprising loosely connected cross shafts, and spaced rotatable cutting disks mounted on the shafts and arranged throughout the frame work to have different closely associated lines of travel, said disks having thin flat cutting peripheries adapted to cut deeply into the soil, in combination with a number of links connecting different shafts and having end bearings of substantial width which surround the shafts and form part of the spacing means for the disks, said links being distributed over the frame work and their bearing ends serving cooperatively to give it sufficient rigidity

against an angular movement in a horizontal plane to disarrange the predetermined relative working positions of the disks without interfering with their free vertical play.

3. In a flexible disk harrow, a flexible frame work comprising a series of transverse shafts, means to loosely connect said shafts in respect to vertical movements only while positively holding them against relative displacement horizontally of the harrow, and a series of cutting disks mounted for independent rotation on each shaft and having flat sharpened annular cutting edges, and elongated cylindrical hubs forming extended bearings for the disks and adapted to coöperate with interposed shaft connecting means to space the disks on their respective shafts, substantially as described.

4. In a flexible disk harrow, a flexible frame work comprising a series of parallel shafts, links to loosely connect the shafts, and a series of disk cutters rotatably mounted on each shaft and having sharpened peripheral cutting edges and elongated cylindrical spacing hubs, which hubs and links are adapted to space the cutters equidistantly on each shaft, and bearings at the outer ends only of said hubs on which they rotate, substantially as described.

5. In a flexible disk harrow, a flexible frame comprising a series of disk shafts, a series of spaced disks rotatably mounted on each shaft and having sharpened cutting peripheral edges and elongated hubs, and links which loosely connect the shafts and have their ends interposed between the hubs of the adjacent disks on the shafts which they serve to connect, the hubs and links serving to equi-distantly space the cutting edges of the disks on the shafts.

6. In a flexible disk harrow, a series of transverse shafts, a row of spaced disks rotatably mounted on each shaft and having hub portions which extend along the shaft on which the disk is mounted, and links which connect said shafts flexibly together and stand in the line of draft of the harrow, each with its ends respectively spaced equidistantly from the forward adjacent disk on one side and the rear adjacent disk on the other side of said link, substantially as described.

7. A flexible disk harrow comprising a series of parallel shafts, diagonal rows of links connecting said shafts, and diagonal rows of cutting disks mounted on the shafts and interposed between the rows of links, each disk having a peripheral sharpened cutting edge and an elongated hub which on each side extends to the adjacent links which connect its respective shaft to an adjacent shaft in the series, said link or links, and said hubs of adjacent disks on each shaft being adapted to equi-distantly space the disks on each shaft.

8. In a flexible disk harrow, a series of shafts, links loosely connecting each adjacent pair of shafts, a series of cutting disks on each shaft, the disks being arranged in 5 diagonal rows from front to rear of the harrow and having as a whole closely associated substantially equi-distantly spaced lines of travel, the disks having spacing hub portions between which the links are received, 10 a number of the hubs on the front and the rear shaft being relatively elongated the width of a link.
9. In a flexible disk harrow, a series of shafts arranged in echelon, a series of equi- 15 distantly spaced disks rotatably mounted on each shaft and arranged in diagonal non-overlapping rows from front to rear, links which loosely connect the adjacent shafts together, and hub portions on the disks 20 which have a length such that they will co-operate with the contiguous links in uniformly spacing the disks on each shaft.
10. In a flexible disk harrow, a series of transverse shafts, parallel rows of links 25 loosely connecting said shafts and extending from front to rear of the frame work of the harrow, said links being arched, and cutters rotatably mounted on the frame work and arranged in parallel rows alternating with 30 and disposed substantially midway between the rows of links.
11. A flexible disk harrow comprising a series of parallel transverse shafts, arched links connecting said shafts and arranged 35 in echelon, straight annular cutting disks mounted on said shafts and also arranged in echelon, the rows of links and disks being arranged alternately and equi-distantly in parallelism, substantially as described.
- 40 12. In a flexible disk harrow, a flexible frame work comprising transverse disk bearing shafts arranged in a series from front to rear of the harrow, links loosely connecting said shafts, and a support comprising 45 links loosely connected parts which are mounted on the links connecting three or more of said shafts and are loosely connected to said links, substantially as described.
13. A flexible disk harrow comprising a 50 series of transverse disk shafts arranged one behind the other, links loosely connecting said shafts, and a support, having relatively movable parts adapted to follow the relative movements of the shafts, which is mounted on and pivotally connected to said links, substantially as described.
- 55 14. A flexible harrow comprising a series of parallel transverse tool shafts, links loosely connecting said shafts to form a flexible frame work, and a support having relatively movable parts pivotally connected to links which couple different pairs of shafts.
- 60 15. In a flexible disk harrow comprising a series of parallel transverse disk shafts, links loosely connecting said shafts, a seat and weight frame having transverse relatively movable members pivotally connected to said links midway between the rows of disks, substantially as described. 70
16. In a flexible disk harrow comprising transverse disk shafts, transverse rows of links loosely connecting said shafts, a seat and weight frame having transverse members movable relatively from front to rear of the harrow and pivotally connected to links of each transverse row at points substantially midway between each of the transverse disk shafts, substantially as described. 75
17. In a flexible disk harrow, a series of transverse disk shafts, arched links loosely connecting said shafts, U-bars loosely connected to the links, a seat and weight frame having relatively movable parts which are loosely connected to said bars, substantially as described. 80
18. The combination with a disk harrow comprising a flexible frame-work, of transverse disk shafts and links connecting said shafts, of a weight and seat platform comprising sections adapted to slide to or from each other from front to rear of the harrow, and arched supports for said sections, each adapted to rest upon links connecting three adjacent shafts, each of said supports being 90 pivotally connected to one link at one end and slidably supported by another link at its other end, substantially as described. 95
19. A flexible disk harrow comprising five transverse disk shafts, links loosely connecting said shafts, arched supporting bars loosely connected to the links connecting the last three shafts, similar bars loosely connected to the links connecting the forward three shafts, and a seat and weight platform 100 connected to said bars, substantially as described. 105
20. The combination in a flexible disk harrow comprising a series of transverse disk shafts, and a series of links loosely connecting said shafts, of a seat and weight support comprising relatively movable members which are loosely connected to centers of links connecting the several shafts to distribute the weight of the seat support uniformly over said shafts, substantially as described. 110
21. A flexible disk harrow comprising a series of parallel disk shafts which are arranged in echelon and have equi-distantly 120 spaced disks thereon, links loosely connecting said several shafts, and draft means connected to the end links and to the link substantially opposite the middle disk on the middle shaft in the harrow, substantially as 125 described.
22. In a flexible disk harrow, a series of transverse disk bearing shafts, links loosely connecting said shafts, two or more of the links which are connected to the forward 130

shaft having portions which project upwardly and extend beyond the periphery of the disks, bracing means connecting the ends of said portions, and draft means also connected to said portions, substantially as described.

23. In a flexible disk harrow, a series of transversely disposed disk bearing shafts, links loosely connecting said shafts, the end 10 links connected to the forward shaft having vertical extensions which project beyond the disk peripheries on that shaft and are provided with alining eyes, a rod which passes through said eyes and has means to brace 15 said extensions, and draft means connected to said extensions, substantially as described.

24. A disk harrow cultivator comprising a frame work consisting of longitudinal and transverse members which are flexibly connected to permit the implement to follow the inequalities of the ground, a large number of closely associated thin cutting disks having wide bearing hubs which are mounted on the transverse members and rotate, said 20 disks being set to turn in a plane parallel with the line of travel of the implement, each disk being positioned to have its separate cutting path distinct from the others, and the several disks being arranged in 25 diagonal rows from front to rear so that their cutting paths follow one behind the other in close parallelism, said longitudinal members of the frame having sufficient bearing engagement with the transverse members 30 thereof to hold the latter against shifting laterally to permit the disks to track.

25. In combination, a parallel series of disk shafts, links loosely connecting said shafts to permit them to freely follow the 40 irregularities of the ground, in doing which the harrow expands and contracts in length, a seat and weight support having relatively movable parts to compensate for the length-wise expansion and contraction of the harrow, and means to mount said support on a 45 plurality of said shafts.

26. In combination with a flexible frame comprising a sequence of transverse parallel relatively movable disk bearings, links connecting the said bearings, a seat and a flexible support for said seat which is mounted on said links and distributes its weight substantially equally over all of said bearings. 50

27. A flexible harrow comprising a series of bearings for disks arranged in transverse 55 parallelism from front to rear of the harrow, means to loosely connect said bearings, an equal number of disks on each bearing, a seat, movably connected seat supports which respectively rest on the forward and rear 60 groups of transverse bearings and which are movable to compensate for the movements of the disk bearings toward and from each other.

28. In a disk harrow cultivator, a series of 65 transverse disk shafts, links having end bearings which receive said shafts and permit them to rise and fall vertically to follow the inequalities of the ground, cutting disks having wide hub bearings mounted to 70 rotate independently on said shafts, the disk and link bearings abutting and inclosing the intermediate portion of the shafts.

29. In a disk harrow cultivator, a series of transverse disk shafts, links having end 75 bearings which receive said shafts and permit them to rise and fall vertically to follow the inequalities of the ground, cutting disks having wide hub bearings mounted on said shafts, the disk and link bearings abutting 80 and arranged both to space the disks equidistantly on the shafts and to inclose the intermediate bearing part of the shaft, and the disk hubs being recessed to form annular chambers adapted to be packed with grease, 85 substantially as described.

In testimony whereof I affix my signature in presence of two witnesses.

HAROLD SHEMWELL.
